UNITED STATES PATENT OFFICE.

JOHN W. McMANAMA, OF WALTHAM, MASSACHUSETTS.

RAILROAD TIE.

Application filed March 1, 1928. Serial No. 258,201.

This invention relates to a railroad tie which includes a body portion of molded concrete, and a metal bar embedded in the concrete body to strengthen the latter, the 5 body being provided with means for engaging track-rail spikes driven into the tie.

One object of the invention is to produce a durable and serviceable tie at a reasonable expense, a discarded track rail being utilized 10 to provide the bar.

Other related objects will hereinafter appear.

Of the accompanying drawings forming a part of this specification,—

15 Figure 1 is a perspective view of the core portion of a tie embodying the invention.

Figure 2 is a fragmentary section on line 2—2 of Figure 1.

20 Figure 3 is a perspective view of the completed tie.

Figure 4 is a fragmentary top plan view, showing a portion of the tie and a portion of a track rail attached thereto.

25 Figure 5 is a section on line 5—5 of Figure 4, the concrete body being shown only by broken lines, and the bar in side elevation.

Figure 6 is a section on line 6—6 of Figures 4 and 5.

30 Figure 7 is a perspective view of the chair plate shown by Figures 4, 5, and 6.

Figure 8 is a perspective view of one of the bushings shown by Figures 5 and 6.

35 The same reference characters indicate the same parts in all of the figures.

In the drawings, 12 designates a concrete body which may be formed in a suitable mold. Embedded in the body is a metal bar provided with a flat upper face which forms a part of the upper surface of the tie, 40 and a channelled lower portion overhung by the upper portion and interlocked with the body. Said bar is preferably made from a length of railroad rail of standard form and including a base 13, a web 14, and a head 15, 45 the bar being inverted, so that its base is uppermost.

The bar is preferably made in two aligned sections, each including a base 13, a web 14, and a head 15.

50 The object of the sectional construction is to permit the insulation of the end portions of the bar from each other, the adjacent ends of the sections being spaced apart at 16. The sectional bar includes means rigidly connecting the sections and preferably embodied in a tie plate 17, bridging the space

at 16, and bolts 18, connecting the tie plate with the webs 14, as shown by Figure 2. The bar also includes means insulating the 60 said connecting means from the bar sections, and embodied in insulation designated by the heavy black lines in Figure 2. In case it is not desired to insulate the end portions of the bar from each other, the bar may be made in one piece.

65 The bar is placed in the mold which forms the body 12, with the base 13 uppermost, the plastic material of the body entering the longitudinal channels between the base 13 and head 15, and enveloping all portions of the bar excepting the upper surface of the 70 base 13, said surface being flush with the upper face of the body. When the plastic material is hardened, the web 14 and head 15 are interlocked with the body 12, as shown 75 by Figure 6.

The base 13 is much wider than the head 15, as usual in railroad rails, and its upper surface, which is flush with the upper surface of the body 12, presents a suitable area 80 of metallic bearing surface at the upper side of the tie.

Figures 4, 5 and 6 show a portion of one of the two track rails attached to the tie, 20 being the base, 21 the web, and 23 the 85 head of said rail. The base of the bar 13 is provided with spike-receiving openings 24, arranged to receive the attaching spikes 25, which secure the track rails to the tie.

The body 12 is provided with vertical 90 spike-engaging bushings 26 (Figures 5 and 6) registering with the openings 24. The spikes 25 are preferably screw-threaded and provided with conical heads 25^a formed to engage the opposite edges of the rail base 95 20, as shown by Figure 5, said heads having squared portions adapted to be engaged by a wrench.

100 The bushings 26 are preferably tubes of indurated fiber, having bores whose diameter is somewhat less than that of the spikes, the fiber being compressible, so that when the spikes are driven by a wrench, their external threads form internal threads in the bushings, the indurated fibrous material 105 imparting suitable strength to the internal threads. The bushings may be incorporated in the body 12, by the molding operation, their upper ends being located partially under the overhanging portions of the 110 bar base 13 and their lower ends seated on the head 15, as shown by Figure 6, so that

said overhanging portions and head oppose vertical movement of the bushings in either direction. The seating of the bushings on the inserted base and head enables the bushings to be conveniently maintained in their predetermined positions before and during the operation of molding the body 12. The molded body confines the bushings between the base and head, and prevents expansion 10 of the external surface of the bushings by spikes driven into the bores thereof. If desired, the bushings may be inserted after the molding operation, in sockets formed for their reception in the body, and the bushings may be split lengthwise, as shown by Figure 8, into sections formed to be separately inserted and assembled in the sockets after the body hardens, the openings 24 in the core base being large enough to receive the sections one at a time. It should be noted that in Figure 5, the body 12 is shown only by broken lines, and the bar is shown in side elevation.

Before attaching a track rail to the tie, a cushioning layer 28 may be seated on the upper side of the tie. Said layer may be composed of fabric and rubber, or otherwise adapted to form a cushion under the track rail.

29 designates a metal chair plate, having spike-receiving openings 30 (Figure 7), arranged to register with the openings 24. The spikes 25 are driven through the several orifices until the inner portions of 35 their conical heads 25^a bear on the rail base 20. The chair plate 29 is provided with raised abutments 31 (Figure 7) on which the outer portions of the conical heads bear when the spikes are fully driven, said abutments preventing the spike heads from slipping or springing out of engagement with the rail base 20.

The abutments are provided with openings 31^a (Figure 7) coinciding with the spike-receiving openings 30 in the chair plate. The inner edges of the abutments bear on the outer edges of the base 20 of the track rail, as shown by Figures 4 and 7, so that the chair plate performs a part of the 50 duty of preventing the spreading of the track.

Figures 4 and 7 show ears 40, formed on one of the abutments 31, and adapted to bear on the upper side of the rail base 20, as indicated by full and dotted lines in Figure 7.

The bar base 13 is provided with upwardly projecting stops 32, adjacent its opposite ends, these stops abutting the outer 60 edges of the chair plates 29, to prevent the spreading of the track. The bottom face 33 of the body is recessed, so that its lengthwise edge portions are lower than its central portion, the bottom face being formed to so 65 engage the road bed material or track bal-

last in which it is embedded, as to oppose lateral or sidewise creeping of the tie on the road bed.

The recessed form of the bottom face enables its end portions, when engaged with a track-lifting jack member, to prevent said member from slipping from either edge of the tie.

To oppose sidewise creeping of the tie, the bottom face 33 may be provided with transverse ribs 34, formed to similarly engage the track ballast. Studs 35 (Figure 3) may be partially embedded in the body 12, to project therefrom and be engaged by means employed for moving the tie to position 80 for use.

It is obvious that the metal bar, characterized as described, may be manufactured as a tie element, without being originally a part of a railroad rail.

I claim:

1. In combination, a railroad tie comprising a molded concrete body and a metal bar embedded therein, and having an upper portion provided with a flat upper face which forms a part of the upper surface of the tie, and a channelled lower portion overhung by the upper portion and interlocked with the body, the upper portion of the bar being provided with spike-receiving openings, and the body with spike-engaging bushings registering with said openings, the bar being provided with upwardly projecting stops adjacent its opposite ends; and chair plates supported by the tie and abutting said stops, said plates being provided with spike receiving openings, registering with the openings in the bar, and with raised spike-head abutments arranged to bear on the outer portions of conical spike heads whose inner portions bear on the outer edges of track rail bases extending across the tie, said abutments being widened to abut the outer edges of a track rail base.

2. In combination, a railroad tie comprising a molded concrete body and a metal bar embedded therein, and having an upper portion provided with a flat upper face which forms a part of the upper surface of the tie, and a channelled lower portion overhung by the upper portion and interlocked with the body, the upper portion of the bar being provided with spike-receiving openings, and the body with spike-engaging bushings registering with said openings, the bar being provided with upwardly projecting stops adjacent its opposite ends; cushioning layers seated on the upper face of the tie, and chair plates seated on the cushioning layers, and abutting said stops, said plates being provided with spike-receiving openings, registering with the openings in the bar, and with raised spike-head abutments arranged to bear on the outer portions of conical spike heads whose inner portions 130

bear on the outer edges of track rail bases extending across the tie, said abutments being widened to abut the outer edges of the track rail base.

5. 3. A railroad tie comprising a metal bar composed of an inverted railroad rail, the edge portions of the inverted base of the rail overhanging the inverted web and head thereof and having rail spike-receiving 10 openings, vertical tubular bushings of compressible material, having lower ends seated on the inverted head, and upper ends seated on the overhanging portions of the inverted base, so that vertical displacement 15 of the bushings in either direction is opposed by said head and base, the bores of the bushings registering with the spike-re-

ceiving openings in the base, and a molded concrete body enveloping the inverted web, the head, and the bushings, said body confining the bushings between the inverted base and head, and preventing expansion of the external surfaces of the bushings by spikes driven into the bores thereof, said bores being expandable by the spikes. 20 25

4. A railroad tie as specified by claim 3, said bushings being tubes of indurated fiber whose bores are adapted to conform to and be internally screw threaded by threaded spikes turned into the bushings. 30

In testimony whereof I have affixed my signature.

JOHN W. McMANAMA.
